UNITED STATES PATENT OFFICE.

FRANK J. TONE, OF NIAGARA FALLS, NEW YORK.

PROCESS OF PRODUCING SILICON CARBID.

1,044,295.

Specification of Letters Patent. Patented Nov. 12, 1912.

Application filed June 14, 1907. Serial No. 379,035.

To all whom it may concern:

Be it known that I, FRANK J. TONE, a citizen of the United States, residing at Niagara Falls, in the county of Niagara and State of New York, have invented certain new and useful Improvements in Processes of Producing Silicon Carbid, of which the following is a specification.

This invention relates to the manufacture of silicon carbid and has for its object the increasing of the efficiency of the process and the output of the furnace.

In the commercial manufacture of silicon carbid a mixture of silica and carbon is subjected to heat in an electric furnace, the heating means being a resistance-core of granular or pulverized carbon. This core offers resistance not only by reason of the specific resistance of the carbon but also on account of the numerous points of poor contact between the discrete particles of carbon.

I have discovered that the efficiency of the process may be considerably increased by employing in place of the core of pulverized or granular carbon a continuous solid carbon core consisting either of a single shaped piece or a series of pieces joined together in a manner to form the equivalent of a single piece.

Referring to the accompanying drawing, in which each of the figures is a horizontal section of a charged furnace:—Figure 1 shows a straight core consisting of a single long carbon rod; Fig. 2 shows a straight core built up of a series of joined pieces; and, Fig. 3 shows a zigzag core built up of a series of joined pieces.

The furnaces illustrated have end walls 1 and side walls 2, of fire brick. Carbon terminals 3 extend through the end walls.

The resistance core 4 shown in Fig. 1 consists of a single long carbon rod, the section and length of the rod being proportioned to give the proper resistance for the voltage and current at which the furnace is to be operated. The ends of the core are connected to the inner ends of the carbon terminals by layers of pulverized carbon 5. The charge 6 completely fills the receptacle and surrounds the core.

It is difficult to obtain carbon rods long enough so that the proper resistance can be conveniently obtained without increasing the length of the furnace beyond practical limits. I therefore show in Fig. 2 a modified core, which consists of a series of two

or more rods or pieces 4' joined end to end by means of closely-fitting carbon collars 7. The resistances of the contacts are thus practically eliminated and the series of rods 60 becomes the practical equivalent of a single rod without joints.

The core shown in Fig. 3 consists of a series of pieces 4'' disposed in a zigzag path from one terminal to the other and joined end to end by carbon blocks 8 into which the ends of the pieces are screwed. By this arrangement the length of the core is increased without increasing the length of the furnace, thus making it possible to expend 70 a greater amount of energy in the same space and obtain a corresponding increase in efficiency.

The several cores are preferably arranged in a horizontal position and supported by 75 the charge, as separate core-supports resting on the base of the furnaces afford direct paths for the escape of heat and decrease the current-efficiency.

This process offers important advantages 80 over that using the pulverized or granular core. These advantages are due principally to the changed thermal conditions and will be apparent upon consideration of the furnace at the end of the run. The core, occupying the central zone of the furnace, is then surrounded by a zone of silicon carbid which in turn is surrounded by a zone of partially reduced or unreduced charge-materials. The specific resistance of granular 85 or pulverized carbon is approximately fifty times that of solid carbon. The solid core therefore will occupy much less space in the furnace and the same volume of silicon carbid will be comprised in a much smaller 90 zone in the case of the solid core than in the case of the granular core, and the outer surface in this zone, which is the surface of the non-productive heat diffusion, will be less.

In other words the losses by radiation will 100 be reduced and the output will be correspondingly increased. Another thermal advantage is that the mass of core-material to be heated to the high temperature of reaction is much less in the case of the solid core 105 than the granular core. Heat thus expended is non-productive or lost heat, only the heat conducted from the core to the charge being productive. Still another gain in thermal efficiency is that the heat expended 110 in the mass of unreduced charge surrounding the smaller silicon carbid zone of the

solid core furnace is less than that expended in the granular core furnace.

The solid core is convenient to place in the furnace and does not contaminate the finished product as does pulverized or granular carbon. The product is better and more abundantly produced than with a granular core.

I claim:

- 10 1. The process of producing silicon carbide, which consists in embedding in a charge of silicious and carbonaceous materials a continuous solid resistance-core consisting of a series of joined shaped resistance-pieces, and passing an electric current through said core.
- 15 2. The process of producing silicon carbide, which consists in embedding in a charge of silicious and carbonaceous mate-

rials a continuous solid resistance-core consisting of a series of joined shaped resistance-pieces supported by the charge, and passing an electric current through said core.

3. The process of producing silicon carbide, which consists in embedding in a charge of silicious and carbonaceous materials a continuous solid resistance-core consisting of a series of joined shaped resistance-pieces arranged in a circuitous path between the terminals, and passing an electric current through said conductor.

In testimony whereof, I affix my signature in presence of two witnesses.

FRANK J. TONE.
